MULTI-RANGE TUNABLE OSCILLATOR

Loren R. Kirkwood, Collingswood, N. J., assignor
to Radio Corporation of America, a corpora-
tion of Delaware

Application June 30, 1936, Serial No. 88,175

12 Claims. (Cl. 250—36)

The present invention relates to a multi-range tunable oscillator for radio receiving apparatus and the like, and has for its object to provide an improved and simplified oscillator circuit adapted to operate in a plurality of wave band or frequency ranges and to provide a predetermined substantially uniform strength of oscillations.

In battery operated and low power receiving apparatus and the like, the available anode potential is limited and, under certain conditions of operation such as operation over a plurality of wide frequency ranges in a multi-wave band receiver, it has been found to be difficult to provide uniform operation and output from the oscillator.

One difficulty encountered in the design and operation of a multi-range oscillator lies in the fact that in any wave band or frequency range a fixed degree of feed back coupling may cause instability of operation at the high frequency end of each wave band or tuning range.

It is, therefore, an object of the present invention to provide an oscillator for low power signaling apparatus and the like such as a battery receiver, in which strong oscillations are generated substantially uniformly throughout each frequency band and in a plurality of frequency bands without instability of operation in the high frequency end of any tuning range.

The range of operation contemplated in connection with circuits embodying the invention may include a total range of from 1,000 to 25,000 k. c., for example, in a series of three bands, each band tunable by a variable capacitor or the like in conjunction with suitable tuning inductances changeable by switching means for each band.

In providing a simplified oscillator system wherein strong oscillations are produced with low voltage power sources, it is also a further object of the present invention to provide an oscillator having an improved coil or inductance element adapted to provide close coupling between a tunable grid circuit and an anode circuit of the oscillator device, whereby, without resulting in instability at the high frequency end of each range, strong oscillations are maintained over a wide operating range through the medium of fixed feed back coupling.

Heretofore, in a multi-range receiving system, it has been considered necessary to provide a plurality of coils or inductances having a relatively high cost of manufacture and utilizing an appreciable space in the apparatus in which they are employed. It is, therefore, a further object of the present invention to provide an improved inductance unit which may be mounted in a rela-

tively small space which is more easily manufactured as a single unit having a high degree of permanence and which provides an improved feed back coupling arrangement in a multi-wave band receiver or in other apparatus requiring an oscillatory circuit tunable over a relatively wide range in a plurality of frequency ranges.

In carrying out the invention a pentode type oscillator device is utilized in conjunction with a single unit coil or inductance system providing a plurality of secondary windings adapted to be tuned through differing frequency ranges as grid circuit inductances and a plurality of primary windings closely associated with the secondary windings on the same coil form and adapted to be used in pairs in each tuning range to provide a high frequency and a low frequency primary for each secondary winding, the low frequency primary for a higher frequency tuning range being further adapted to form the high frequency primary for the next lower frequency tuning range.

In order to provide a uniform oscillator output over a wide tuning range, the low frequency primary is tuned below the tuning range of the oscillator grid circuit for the selected frequency band and the high frequency primary is tuned above the high frequency end of the selected frequency band, and since the maximum feed back is obtained at primary resonance, the use of the two primary windings tuned as above described results in a more uniform feed back or oscillator output throughout the tuning range in any band of frequencies.

The invention will, however, be better understood from the following description when considered in connection with the accompanying drawings and its scope will be pointed out in the appended claims.

In the drawings, Fig. 1 is a schematic circuit diagram of an oscillator system embodying the invention and adapted for use in conjunction with a multi-wave band receiver.

Fig. 2 is a side view, in elevation, of the inductance unit of the system shown in Fig. 1.

Fig. 3 is a detail view in cross section and on a greatly enlarged scale, of a portion of the inductance unit of Fig. 2, showing the arrangement of the windings thereof, and

Figs. 4, 5 and 6 are schematic circuit diagrams showing the switching connections provided in the system of Fig. 1 for the three differing wave band portions of the switching means therein, and the relation of the windings on the inductance unit for the differing frequency ranges of operation provided by the circuit of Fig. 1.

Referring to Figs. 1, 2 and 3, 5 is an oscillator tube of the pentode type having a cathode 6, an output anode 7, a suppressor grid 8 connected with the cathode 6, a screen grid 9 and a control grid 10.

The control grid is connected to the cathode through a grid resistor 11 and is coupled to the tunable grid circuit hereinafter described, through a grid coupling capacitor 12 in the grid 10 or high frequency lead 13 of the oscillator grid circuit, across which circuit is connected the main variable tuning capacitor 14. In the system shown, all return circuits are made to chassis or ground indicated by the various ground connections as designated at 15, for example. The oscillator grid circuit is also coupled to a first detector or frequency changer tube 16 through a coupling capacitor 17 and a grid lead 18 in connection with the first or inner grid 19 of an RCA 20 8L7 or pentagrid mixer amplifier, as indicated in the drawings.

Signals are applied to the detector in connection with the inner control grid indicated at 20 and are supplied thereto from an input circuit 25 indicated generally at 21 and tunable through corresponding frequency ranges with the oscillator by means of a second main variable capacitor indicated at 22.

The grid 19 and the grid 20 are both connected 30 to sources of bias potential, through grid resistors indicated at 23. The intermediate frequency output is taken from the first detector 16 through an intermediate frequency output transformer 24. As the detector does not further concern the 35 present invention, further description is not believed to be necessary.

The oscillator circuit comprises a series of inductances 30, 31 and 32 for frequency or wave band ranges which may be designated as bands 40 C, B and A, respectively covering a frequency range in three differing continuously tunable bands between 1,000 k. c., for example, and 25,000 k. c., the higher frequency band being the C band and B and A bands being tunable 45 through progressively lower frequency ranges.

For example, the C band may be tunable through a frequency range of from 6,400 to 22,460 k. c., the B band may be tunable through a frequency range from 2,000 to 6,400 k. c., and the A band may cover a range of from 1,000 to 2,000 k. c. Such frequency ranges represent any suitable apportioning of tuning range in each band, whereby the same tuning capacitor 14 may cover the selected band by operation through substantially its full tuning movement.

The secondary windings 30, 31 and 32 are each connected at one end with ground as indicated at 34 and at their opposite ends are connected through leads 35, 36 and 37 with switch contacts 60 38, 39 and 40, respectively on a wave band change switch 33 forming one unit of a gang switch for the detector and other tuning circuits of the receiver. The switch unit shown is adjusted for C band operation, and in this position the contacts 39 and 40 are arranged to be connected to a ground contact 41 through a movable insulated contact shorting element 42 whereby the secondaries not in use are short-circuited and rendered ineffective for reducing the amplitude of oscillations set up in the selected secondary 30 for the C band.

The lead 35 in connection with the contact 38 is connected with a movable insulated contact element 42 which, in the position shown, engages the contact 38 and at the same time is in con-

nection with an arcuate contact strip 44 having a terminal 45 connected with the grid lead 13 of the oscillator. The oscillator circuit is further loaded by a shunt resistor 46 connected between the grid lead 13 and ground. The oscillator circuit 50 30—14 is thus connected with the grid 10 of the oscillator for applying oscillations thereto with the switch in the position shown.

Each of the secondary windings is provided with a suitable shunt trimmer capacitor 47 and the A band secondary 32 is further provided with a fixed shunt tuning capacitor 48 for causing it to cover the desired frequency range. For causing the oscillator inductance in certain of the bands to "slow up" the tuning of the oscillator circuit, that is, to cause the oscillator circuit tuning to change at a different rate to track with the other tunable circuits when tuned by the variable capacitors 14 and 22, series capacitors 49 and 50 are provided in the grid circuits of 20 the two lower frequency bands. Because of the coil arrangement hereinafter described, this additional capacitor is not required for the high frequency C band.

To provide suitable feed back energy over a 25 relatively wide tuning range such as that required in the receiver of the present example, a plurality of primary windings or winding sections are provided in close association with and between the secondary windings as indicated at 55, 30 56, 57 and 58 and are connected in series with each other, as shown, in the oscillator anode output circuit indicated at 59—60, the latter lead extending from the lower-most coil 58 to an anode positive potential supply lead 61, and the former lead serving to connect the oscillator anode with the high frequency end of the high frequency primary section 55.

The latter is preferably wound between the turns of the high frequency secondary winding 40 30 as indicated more clearly in detail in Fig. 3. It will be noted that the winding form indicated at 53 is provided with grooves 61 for spacing the secondary turns and holding them in predetermined fixed spaced relation and that the winding 45 form is similarly grooved between the main grooves for the secondary turns as indicated at 62, to receive the winding 55 whereby a relatively high degree of feed back coupling is provided between the winding 55 and the winding 30 50 39 without introducing undesirable mechanical and electrical features and without an abnormally large number of feed back turns. The coil terminals are provided at one end of the coil form as indicated at 53, and it will be noted that all 55 of the windings occupy a relatively small space on the form which is shown in Fig. 2 substantially full size.

In the coupling system shown, the plate and grid windings are interleaved to provide closer coupling than could be provided by placing the windings end to end, and at the same time a relatively low degree of capacity coupling exists because of the difference in sizes of the conductors.

In many oscillator circuits, the oscillator may shift in frequency with changes in signal input to the receiver because of changes in automatic volume control bias and, therefore, changes in potential on the oscillator, to such a degree that 70 the oscillator may flutter on strong signals. This condition is overcome by the reduction in the size of the feed-back coil required, through interleaved windings, and also the operation in regard to stability is improved by reducing the size 75

of the grid capacitor 12 with a corresponding change in the grid resistor 11, so that in the circuit shown the oscillator is stable over the full operating range in any frequency band.

5 This follows that a fixed relation is provided between the plate inductance, the mutual inductance of the plate coil to the grid coil, and the values of the grid condenser and resistor with respect to the input resistance and impedance of the tube used as the oscillator.

10 For example, in the system shown, with an oscillator tube 5 of the type known as the RCA 1B4, with a grid resistor 11 of 150,000 ohms and a grid capacitor 12 of 33 micromicrofarads, the oscillator circuit is stabilized in conjunction with the coil system shown, through the high frequency or C band tuning range, as well as throughout the lower frequency tuning ranges for the B and A bands.

15 The switch 33 is provided with further contacts arranged diametrically opposite to the contacts for the secondary windings, for changing the connections with the primary windings and, in the present example, such contacts comprise 20 three contacts 65, 66, and 67 connected together by a movable arcuate contact strip 68 similar to and lying in the same plane of rotation as the contact strip 42, while below and spaced from the contact strip 68 and on a plane with the contact element 44 are two arcuate contact elements 69 and 70 having terminals 71 and 72 respectively.

25 A movable insulated contact element 73 serves to connect the arcuate contact element 70 with a terminal 74 while the contacts 65, 66 and 67 are interconnected by the movable contact element 68. A lead 75 is connected between the contact 74 and a tap point 76 between the primary windings 55 and 56.

30 A second lead 77 is connected between the contact 65 and a tap point 78 between the primary windings 56 and 57, and a third lead 79 is provided between the contact 66 and a tap point 80 between the primary windings 57 and 58. The contact 67 is connected through a lead 81 with the low potential lead 60 of the anode circuit.

35 The terminal 72 is connected to ground through a lead 82 and a primary tuning capacitor 83 in said lead for the C band while the terminal 71 is connected to ground through a lead 84 and a primary tuning capacitor 85 for the A and B bands.

40 The B potential supply lead 61 is also connected to the screen grid 9 of the oscillator 5, through suitable filter means comprising a series resistor 90 and by-pass capacitors 91-92. It will also be noted that the oscillator cathode 6 is connected to ground as indicated at 93.

45 It will be seen that a plurality of primary and secondary windings are arranged in close spaced relation to each other on a single winding form, with the primary winding sections arranged to be closely coupled with adjacent secondary windings and the switching arrangement for the primary sections is such that as the secondary windings 30, 31 and 32 are progressively connected to the oscillator tuning capacitor and input circuit lead 13 for tuning through a predetermined 50 range, the primary winding connections are, at the same time, changed to conform therewith. The various connections may be understood by considering that the switch 33 comprises the rotary movable elements 43 and 73 engaging the 55 lower arcuate contact strips 44 and 70 and 69

progressively as the rotary element of the switch is moved in the direction of the arrow. At the same time the upper, insulated, moving contact-shorting strips 42 and 68 move with the contact elements 43 and 73 progressively to remove the 5 short circuit from 65, 66, and 67 and 39, 40 and 41 but do not engage the contacts 71 and 72.

10 The circuit connections provided by the switch will be better understood with reference to Figs. 4, 5 and 6 for the C, B and A band connections respectively and in which the same reference numerals are applied to the same parts as in Fig. 1.

15 Referring to Fig. 4, the C band connection as provided in Fig. 1, is indicated, and it will readily be seen that the secondary inductance 30 is connected with the oscillator grid 10 to provide a tunable secondary circuit in conjunction with the tuning capacitor 14 and that the anode 7 is coupled back to the secondary winding 30 20 through the primary winding 55 and the winding 56 and that the latter is provided with the shunt tuning capacitor 83.

25 The inductance of the winding 55 is such that it naturally tunes to a frequency above the tuning range of the secondary or grid circuit of the oscillator, while the winding 56 is tuned by the capacitor 83 slightly below the lowest frequency in the tuning range in the grid circuit, whereby a relatively strong and uniform feed back of energy is provided throughout the tuning range of the C band without causing the oscillator to become unstable at the high frequency end, as is normally the case where a single winding is arranged for this purpose. 35

30 Since the windings 57 and 58 are short circuited by the switch contacts they are not included in circuit and the anode or feed back circuit is represented by the heavy circuit lines in connection with the anode circuit. At the same time it 40 will be noted that the second windings are short circuited to ground as indicated at 95. This ground connection is that provided in connection with the contact 41 of Fig. 1.

35 Omitting the tube from the connections for the purpose of simplifying the drawing, it will be noted in Fig. 5 the B band connections provide for the primary windings 56 and 57 to function in connection with the secondary winding 31 which is connected to the grid circuit and tuning element 50 of the oscillator while the secondary 32 is short-circuited to ground. Likewise the primary winding section 58 is short-circuited and the feed back circuit is indicated in heavy lines.

40 In this connection, the capacitor 85 is connected 55 in shunt with the primary winding section 57, which forms the low frequency primary for the B band while the winding 56 provides the high frequency primary and is arranged to tune above the B band in frequency while the low frequency 60 primary is tuned below the B band. The primary winding 55 also remains in circuit and may be assumed to couple with the secondary winding 51 to a limited extent.

45 Since the C band is relatively high in frequency 65 with respect to the B band, the secondary winding 30 does not require short-circuiting and the primary winding 55 does not require elimination from the anode circuit.

50 Referring now to Fig. 6 for the A band connections, it will be seen that the primary windings 57 and 58 are in series on either side of the secondary winding 32 which is connected to the oscillator grid and tuning means, while the primary sections 55 and 56 remain in circuit to aid in the 55

coupling without in any way effecting the operation of the system to prevent feed back. The primary winding section 58 is tuned to a frequency below the A band by the capacitor 85 which is now connected in shunt with it as shown and thereby provides the low frequency primary, while the winding 57 provides the high frequency primary.

From the foregoing description, it will be seen that an oscillator tuning system is provided in which a series of secondary windings are selectively connectible with an oscillator grid electrode and tuning capacitor by simple switching means and that the secondary windings are associated with a plurality of series connected primary sections, all of which are connected in series with the oscillator anode circuit and operated in pairs, progressively, as high and low frequency primary windings, the low frequency primary winding of a higher frequency tuning band being utilized as the high frequency primary winding for the next lower frequency band and that the switching operation is simplified to the extent that it is merely necessary to progressively remove a short circuit from the lower frequency primary windings for the lower frequency ranges and to apply a shunt tuning capacitor to the low frequency primary winding for each band, which primary winding is the high frequency primary winding of the next lower frequency band.

The two windings are utilized to prevent instability at the high frequency end of the tuning range in each band and to permit strong enough feed back or oscillator output, that is, or effective feed back, at the low frequency end of the tuning range in any band, whereby the strength of the oscillations is more uniform.

In the higher frequency tuning ranges, the double grooved winding arrangement, wherein the anode winding is included between the turns of the grid winding but spaced therefrom as shown in Fig. 3, for example, has the additional advantage that it cuts down the leakage and permits enough energy transfer to provide strong oscillations at the low frequency end of the tuning range without permitting instability at the high frequency end of the tuning range when associated with the low frequency primary winding.

Furthermore, in the C or highest frequency tuning range, because of the close coupling of the primary windings, the series tracking capacitor for the C band is not required. Because of the pentode having a screen grid and a suppressor grid connection, the coupling which would otherwise cancel because of capacity from grid to anode is prevented and the oscillations are maintained throughout a wide frequency range.

I claim as my invention:

1. A multi-range tunable oscillator comprising in combination, an anode circuit, a grid circuit, variable tuning means in said last named circuit, an inductance unit comprising a series of primary windings connected in series relation in said anode circuit, a series of grid windings interposed between said primary windings in said unit, means for selectively connecting each of said grid windings with said tuning means and grid circuit, means for connecting in pairs said primary windings more adjacent to a selected grid winding, and means for causing one of said primary windings to operate as a low frequency primary winding for a higher frequency tuning band in association with said selected grid winding and as a high frequency primary winding in association

with another selected grid winding for the next lower frequency band.

2. A multi-range tunable oscillator in accordance with claim 1, further characterized by the fact that the grid circuit is coupled to the variable tuning means and said grid windings through a coupling capacitor having a relatively low capacity, and that a primary winding in association with one of said grid windings for the highest frequency band is interleaved therewith, the turns of said primary winding being wound between the turns of the grid winding and spaced therefrom.

3. An oscillator for a multi-waveband radio receiver, comprising in combination, an electric discharge oscillator device, an inductance unit therefor having a plurality of secondary windings adapted to be tuned through differing frequency ranges, means for selectively connecting each of said windings with said device as a grid circuit inductance therefor, a plurality of primary windings associated with and interposed between said secondary windings in said unit, an anode circuit for said device, and means for selectively connecting two of said primary windings on opposite sides of a selected secondary winding, serially in pairs in each tuning range, said primary windings providing a high frequency and a low frequency primary for each secondary winding, and means for causing the low frequency primary for a higher frequency tuning range to provide the high frequency primary for the next lower frequency tuning range.

4. In a multi-wave band oscillator for a radio receiver, a tuning system as defined in claim 3, further characterized by the fact that in each wave band the low frequency primary is tuned below the tuning range of the secondary winding for a selected frequency band and the high frequency primary is tuned above said tuning range, whereby a maximum feed-back at primary resonance and a more uniform feed-back and oscillator output throughout the tuning range in any band of frequencies is obtained.

5. An oscillator tuning system for a multi-wave band receiving system comprising in combination, a tuning unit comprising a series of secondary windings, variable tuning means selectively connectible with said windings, a plurality of primary windings interposed between said secondary windings, an oscillator anode circuit in which said windings are connected in series, means for operating said primary windings in pairs as high and low frequency primary windings in relation to a predetermined secondary winding, and means for causing the low frequency primary winding of a higher frequency tuning band to operate as the high frequency primary winding for the next lower frequency band.

6. An oscillator tuning system in accordance with claim 5 further characterized by the fact that the lower frequency primary windings exclusive of one in an operative pair are short circuited, that means are provided for progressively removing the short circuit from a lower frequency primary winding in a pair for the next lower frequency range, and that a tuning capacitor and means for applying said capacitor in parallel with the low frequency primary winding for each band are provided.

7. An oscillator system for a multi-wave band radio receiver comprising in combination, an electric discharge oscillator device having a grid circuit and an anode circuit, means for variably tuning said grid circuit, and means for adjusting

- said oscillator for operation throughout a plurality of frequency ranges comprising a series of secondary windings tunable by said tuning means through differing frequency ranges in connection with said grid circuit, selective switching means for connecting each of said windings with said tuning means, said secondary windings being arranged in coaxial spaced relation to each other, a plurality of primary windings interposed between said secondary windings, said switching means including contacts connected with said primary windings, and switching connections providing in the anode circuit a pair of primary windings as effective coupling means with a selected secondary winding at opposite ends thereof, means for tuning one of said primary windings to a frequency above the tuning range of said secondary winding and the other of said primary windings being responsive to a frequency below the tuning range of said secondary winding whereby uniform feed-back is provided for said secondary winding throughout the tuning range thereof and said switching means further including contacts connected with said primary windings whereby the low frequency primary winding is effective as a high frequency primary winding in association with a secondary winding for the lower frequency tuning range.
8. In a multi-wave band radio receiver, a tunable oscillator system comprising variable tuning means, a single tuning unit comprising a plurality of inductive windings and selective switching means connected between said tuning means and said inductive windings for selectively connecting certain of said windings in circuit with said tuning means and others of said windings in pairs in association with a selected winding to provide a high and low frequency primary therefor, the primary connection being such that a low frequency primary winding for one selected winding is effective as a high frequency primary winding for another of said selected windings.
9. In a multi-wave band radio receiver, a tunable oscillator system as defined in claim 8 further characterized by the fact that the primary windings are interposed between the selectable windings for said tuning means and that certain

of said windings are interleaved, the turns of one winding being interposed between and spaced from the turns of another of said windings to provide a high degree of coupling.

10. In a multi-wave band tunable oscillator system, the combination of an inductance unit therefor comprising a series of windings arranged in spaced coaxial relation to each other, a common winding form therefor on which said windings are mounted, variable tuning means, means for connecting alternate windings selectively each with said tuning means whereby said windings are tunable through differing frequency ranges, and means for connecting windings at opposite ends of a selected winding in series to provide a pair of primary windings therefor, means for tuning one of said primary windings below the frequency range through which the selected winding associated therewith is tunable, said primary winding being responsive to a frequency above the tuning range of another selectable alternate winding for a next lower frequency range, and means for connecting said primary winding as a high frequency primary winding for said last-named alternate winding in said next lower frequency tuning range.

11. In an oscillator for a battery operated receiver, an oscillator circuit comprising a plurality of secondary windings selectively connectible into the oscillator circuit, means providing a high and a low frequency primary winding in coupled relation to each of said secondary windings, and means for connecting the low frequency primary for a higher frequency secondary winding in circuit to provide a high frequency primary winding for a lower frequency secondary winding.

12. An oscillator in accordance with claim 11 further characterized by the fact that an oscillator device is provided therein comprising an electric discharge pentode tube having a grid circuit selectively connectible with said secondary windings, and an anode circuit in series with said primary windings to supply oscillations thereto.

LOREN R. KIRKWOOD.
